UNITED STATES PATENT OFFICE.

CLIO B. YAW, OF ARLINGTON, NEW JERSEY, ASSIGNOR, BY MESNE ASSIGNMENTS, TO
REMINGTON TYPEWRITER COMPANY, OF ILION, NEW YORK, A CORPORATION OF
NEW YORK.

TYPE-WRITING MACHINE.

1,141,857.

Specification of Letters Patent. Patented June 1, 1915.

Application filed March 1, 1912. Serial No. 680,785.

To all whom it may concern:

Be it known that I, CLIO B. YAW, citizen of the United States, and resident of Arlington, in the county of Hudson and State of New Jersey, have invented certain new and useful Improvements in Type-Writing Machines, of which the following is a specification.

My invention relates particularly to paper feeding, guiding and controlling mechanism for typewriting machines and its general object is to provide improved mechanism of the character specified.

More specifically stated, one object of the invention is to provide novel end stop or gaging devices for coöperation with the paper when it is introduced at the front of the machine.

Another object is to provide end stop or gaging devices of the character specified in combination with a paper guide or deflector which is movable away from the platen when the end stops are moved toward the same.

Another object is to provide means for releasing the paper feeding devices that coöperate with the platen and for concurrently moving the end stops to operative position and moving the paper deflector away from the platen so that paper may readily be introduced at the front of the machine and pushed backwardly around the same until gaged by said end stops or gages.

Another object is to provide holding or detaining devices associated with means of the general character last stated.

Another object is to provide side gaging devices for the paper in connection with paper controlling means of the character stated above.

Other objects will hereinafter appear.

To the above ends my invention consists in the features of construction, combinations of devices and arrangements of parts hereinafter described and particularly pointed out in the claims.

In the accompanying drawings which illustrate one form of my said invention as applied to the platen carrier or carriage of a No. 11 Remington front-strike typewriting machine, Figure 1 is a fragmentary top plan view of the platen and platen carrier showing my invention applied thereto. Fig. 2 is a longitudinal sectional view of the sup-

porting and controlling devices for the end stops or gages. Fig. 3 is a detail face view of the friction disk or washer included in the mounting of said end stops or gages. Fig. 4 is a vertical sectional view taken on a plane designated by the line $\alpha-\alpha$ in Fig. 1 and looking in the direction of the arrows at said line. Fig. 5 is an operating view of parts shown in Fig. 4. Fig. 6 is a fragmentary perspective view illustrating the mounting of the paper deflector.

In the drawings, the platen 1 is supported on an axle 2 which bears in the end bars 3 of a platen frame or carrier which further includes a connecting cross bar 4 under the platen. The platen frame is shiftably mounted on a rectangular carriage truck which comprises front and rear bars 5 and 6 and connecting end bars 7, the front and rear bars 5 and 6 being grooved to coöperate with roller bearings on the frame of the machine.

The cross bar 4 has secured to it angular brackets 8 which provide bearings for a rock shaft 9, said rock shaft also bearing in the end bars 3. The rock shaft 9 supports a paper guiding member or combined paper table and deflector 10 which is not claimed *per se* by me, it, together with the means of supporting and controlling the same, being the invention of Alfred D. Maury and described and claimed in his application, Serial No. 655,669, filed October 20, 1911, to which application reference may be had for a fuller description of the combined table and deflector than that contained herein. The rock shaft 9 also supports the two sections 11 comprising the main feed roller, which sections are arranged in line with each other and coöperate with the platen 1 some distance inward from its ends and at the rear under side thereof.

Each roller section 11 is pivoted in a carrier 12 which bears loosely on the rock shaft 9 and is prevented from moving endwise of said shaft by a collar 13 and a crank arm 14 fixed thereto inside the ends of the carrier. A spring 15 coiled around the shaft 9 between said collar and said crank arm and fixed at one end to said collar engages at its other end with the carrier 12 and presses the associate roller section 11 constantly toward the platen. The crank arm 14 is adapted to engage at its outer end with the

cross bar of said holder and when the shaft 9 is rocked operates on the holder to overcome the spring 15 and release the roller 11. This construction differs slightly in detail from 5 that disclosed in the application of Maury aforesaid but the principle of operation is the same. Arranged near each end of the platen and in line with the feed roll sections 11 but outside the same are short terminal 10 pressure rolls 16, each mounted on a rod 17 which is supported on a carrier 18 similar in construction to the carrier 12 and comprising end portions and a connecting cross bar, the end portions being pivoted on the 15 shaft 9. Collars 19 fixed to the shaft prevent endwise movement of the carriers 18 and a coiled spring 20 is associated with each carrier 18 to press the roll 16 toward the platen, said spring 20 being secured at 20 one end to one of the collars 19 and at its other end engaging with the cross bar of the carrier 18. Unlike the main or intermediate rollers 11 the terminal rolls 16 are not releasable from the rock shaft 9, so that when 25 the shaft is rocked the rolls 16 will not be affected, said rolls remaining constantly in spring pressed engagement with the platen or the paper thereon.

The combined paper table and deflector 30 or guide member 10 is inclined downwardly toward the platen at its rear and the lower portion of said member is curved to conform to the shape of the platen rather closely at the front and under side of the 35 platen, terminating somewhat below the printing line and normally contacting with the platen or the paper thereon.

As indicated at 21 the member 10 is slotted to provide openings through which 40 the pressure rolls 11 and 16 coöperate with the platen. The paper table portion of the member 10 extends upward and rearward away from the platen at the rear side thereof, and terminates at a considerable distance 45 above and behind the platen. In the present instance a U-shaped bar 22 is secured as by rivets 23 to the upper portion of the member and provides an extension thereof which is adapted to support extra long sheets of 50 paper. The member 10 is supported at three points or places as follows. Secured to its lower portion near each end is an angular bracket 24 which, as clearly shown in Fig. 6, is pivotally connected at 25 with 55 an arm 26 comprised in a supporting bracket which includes also bearing portions 27, a connecting cross arm 28 and a downward extension 29 from one of the bearing portions 27. The bearing portions are pivoted loosely on the shaft 9 and each extension 29 is connected by a draw spring 30 with the frame bar 4, said draw springs operating to maintain the member 10 in contact with the platen, as shown in Fig. 4. 60

65 The middle of the upper portion of the

member 10 is slidably supported on the platen frame by devices comprising a bracket 31 which is secured to the rear of the member 10 and adjustably supports by a screw 32 a guide member 33 slotted at 34 to engage with a guide rod or cross rod 35 which is secured at its ends as by screws 35^a to extensions 3^a on the end bars 3. The slot 34 is inclined downward and forward and the disposition of the pivots 25 with respect to the rock shaft 9 is such that they will, when the rock shaft 9 is turned, move downward and forward in a path substantially parallel with the angle of the slot 34, this movement being caused by crank arms 36 fixed to the rock shaft 9 and arranged to co-operate with ears 26^a extending laterally from the arms 26 near their outer ends. As a result of the impulse communicated from the rock shaft 9 through the crank arms 36 and ears 26^a to the guide member 10, said member 10 will have what is commonly referred to as a parallel motion, that is, points or parts of it will move in parallel paths; and when released or moved away from the platen the member 10 will occupy the position shown in Fig. 5, providing a passage way or opening *a* extending between the member 10 and the platen 1, the passage way beginning at the front of the platen 95 and somewhat below the printing line and extending downward around and beneath the platen.

The devices for rocking the shaft 9 to release the main feed roller 11 and the 100 guide member 10 in the manner described comprise a crank arm 37 secured to the rock shaft 9 outside the left-hand end bar 3 and extending normally forward and upward as shown in Fig. 4. Pivoted at 38 to the crank 105 arm 37 is the lower end of an eccentric strap 39, the upper end of which is formed with an eye into which fits an eccentric boss 40 on the inner face of an eccentric carrying member 41, the upper end of which member terminates in a handle or finger piece 42. The member 41 bears at 43 on a shouldered screw projecting laterally from an upward extension 3^b on the left-hand end bar 3.

Stop shoulders 44 and 45 on the member 115 41 are adapted to coöperate with a stop pin 46 on the strap 39 to limit the turning movements of the eccentric member 41, the shoulder 44 normally coöperating with the pin 46 as shown in Fig. 4. If the key or finger 120 piece 42 be pushed rearward from the Fig. 4 to the Fig. 5 position, the latter position being determined by the engagement of the shoulder 45 with the pin 46, the eccentric 40 turning about the pivotal axis 43 will be 125 lowered, causing the eccentric strap 39 to swing downward until the eccentric is brought nearly on a dead center; and the parts will be maintained set in the Fig. 5 position, friction devices being preferably 130

provided to assist in thus maintaining the parts. The downward movement of the eccentric strap 39 as described turns the crank arm 37 downward, rocking the shaft 9 and causing the arms 14 to release the feed rollers 11. Concurrently the arms 36 acting against the ears 26 will rock the supports 26-29 against the springs 30, actuating the guide member 10 so that the deflector portion will move in a substantially radial direction and provide the opening or passage-way *a* at the front and lower sides of the platen.

The mechanism thus described is particularly adapted to what is commonly termed "front feeding," that is, the initial insertion of work sheets backward from the front side of the platen instead of the common method of insertion at the rear of the platen. In making use of the devices thus far described for "front feeding," I prefer to associate with them gaging devices which are arranged to cooperate with the rear or bottom edge of the sheet or sheets so as to stop the sheets as inserted from the front of the machine and properly gage them.

As herein exemplified the gaging devices comprise two stop arms 47 terminating at their lower ends in off-set end portions which constitute stops or gages proper 48. The gaging or stop devices 48 are adapted to move toward and away from the platen behind the same and somewhat below the horizontal plane containing its axis through slots or openings 50 in the guide member 10 when the arms 47 are moved or swung as now to be described. Said arms are so disposed lengthwise of the platen (Fig. 1) that the stops 48 will come in the spaces between the outer pressure roll 16 and the main feed roller sections 11, although the stops are somewhat above the bite of the rollers. The arms 47 incline upward and rearward behind the member 10 and at their upper ends are adjustably clamped by clamping screws 49 in kerfs 51 formed in bearing blocks or crank arms 52 secured by screws 53 to a sleeve or tube 54 which bears on the rod 35, said sleeve abutting at its left-hand end against the inner face of the left-hand extension 34, the right-hand end of said sleeve terminating a short distance to the right of the right-hand stop arm 47. The right-hand end of the sleeve 54 carries a friction disk 55 having a collar portion which is secured by set screws 56 to the sleeve. A cooperating oppositely faced friction disk 57 is similarly secured by set screws 58 to the rod 35 just to the right of the sleeve 54 and disk 55 (Figs. 1 and 2). Arranged between the inner faces of the disks 55 and 57 is a friction device or washer 59 shown detached in Fig. 3. Said washer is provided with a central opening 60 which fits loosely over the sleeve 54 and also with a plurality of

other openings or cut-outs 61 having mouths 62. At the sides of these mouths the metal forming the washer is bent out of the plane of the washer as indicated at 63, providing a number of slightly projecting spring 76 tongues.

The washer 59 is depressed between the disks 55 and 57 and generates sufficient friction against the disk 55 to hold the sleeve 54 carrying the stop arms in adjusted positions when said sleeve has been turned or given rotary movement on the bearing rod 35.

Preferably the sleeve is connected to the member 41 so that an operation of the key 42 may not only release the main feed roller and the deflector or guide member 10 but may also move the stops 48 into operative position through the openings 50. The devices constituting the connection include a crank arm 64 suitably secured to the left-hand end of the sleeve 54 and projecting oppositely from the crank arms 52. The crank arm 64 is provided at its free end with a headed screw 65 off-set to the left as shown in Fig. 1 and supporting a sleeve 66. A link 67 connects the member 41 with the crank arm 64. The forward end of said link is pivotally connected at 68 with the member 41 and the rear end of said link is formed with a slot 69 which engages with a shank of the screw 65, the link being loosely confined between the head of said screw and the sleeve 66. As shown in Fig. 4 the forward end of the slot 69 is normally engaged with the screw 65 and at this time the stops 48 are retracted so that they are entirely below the front or upper surface of the member 10. When the key 42 is pushed rearward from the Fig. 4 to the Fig. 5 position the slotted rear end of the link 67 will be moved longitudinally forward, and toward the latter end of the movement of the key 42 the rear end of the slot 69 will engage with the screw 65 and will operate on the crank arm 64 to swing the latter forward, turning the rock shaft so that the supporting arms 52 will swing the stop arms 47 forward, causing the stops 48 at the lower ends thereof to pass forward through the openings 50 to the operative position shown in Fig. 5. In this position it will be observed that while the stops 48 have passed part way through the openings 50 and project beyond the forward face of the member 10, they do not engage with the platen surface.

It will be understood that by pulling the key 42 back from the Fig. 5 to the Fig. 4 position the stops or gaging devices 48 will be retracted to inoperative position while the feed rollers 11 and the forward portion of the guide member 10 will return to cooperative engagement with the platen. The operation of the key does not affect the terminal rolls 16 which constantly remain en-

gaged with the platen. The connections between the key and the stops 48 are normally passive as distinguished from constructions embodying springs which press the stops 5 normally in one direction or another.

Associated with the paper feeding and controlling devices above described I preferably employ a side gage or guide 70 adjustably supported on the rod 35 near the 10 right-hand end thereof and extending forward from the same, terminating close to the rear, upper side of the platen. Also I employ a spring bail or pressure device to cooperate with the front, upper side of the 15 platen, said device comprising side arms 71 and a connecting cross rod 72 provided with pressure rolls 73. The arms 71 are fixedly supported on a rock shaft 72* which bears in brackets 74 secured to the front bar 5 of the carriage truck. Draw springs 75 are connected to the brackets 74 and the arms 71 and exert a pressure on the bail to maintain the rolls 73 in operative engagement with the front side of the platen above the printing 20 line. Preferably also a side guide or gage 76 is adjustably supported on the cross rod 72 near the left-hand end thereof. The gage 76 is intended to coöperate with the left-hand edge of a bill sheet 77 which is introduced from the front and which is of less 25 width than the distance between the terminal rolls 16 so that the gage 76 is adjusted somewhat to the right of the vertical plane of the left-hand roll 16. The rolls 16 co- 30 operate with the side margins of a wide record sheet 78 which is introduced into the machine from the rear in the usual way, the side gage 70 coöperating with the right-hand edge of said record sheet to position it prop- 35 erly lengthwise of the platen.

Assuming the record sheet 78 to be in place and that it is desired to introduce a bill sheet, such for example as a tax bill, which is the character of bill for which the 40 present exemplification of my invention was particularly designed, the operator pushes the key 42 rearward from the Fig. 4 to the Fig. 5 position, thereby releasing the main feed roller 11, 11, moving the paper guiding member 10 away from the platen and opening the passage α , and swinging the end stops or gages 48 forward substantially radially of the platen through the openings 50 in the guide member 10. The operator then inserts from the front of the machine the lower or bottom end portion of the bill sheet 77, guiding the left edge of the latter against the side gage 76 and pushing the sheet 77 downward and rearward through the opening α under the platen, the side edges of the sheet passing between the engaged end rolls 16 which at this time are maintaining the record sheet held or clamped against the platen. The rearward movement of the bill 45 sheet continues until its bottom edge con-

tacts with and is arrested by the end stops 48 (Fig. 5) which serve to gage or align the bottom edge of the sheet.

Owing to the tendency of the sheet to straighten out, its bottom edge during its rearward movement will continue in contact with the face of the guide member 10 and will be certain to engage operatively with the stops 48 so that it is not necessary for the stops 48 to project any farther forward through the guide member 10 than is shown in Fig. 5. The sheet 77 having thus been properly positioned the key 42 is pulled forward restoring the main feed roller and the guiding member 10 to coöoperative engagement with the paper. By reason of the frictional mounting of the stop arms 47 and also of the lost motion connection 65, 69, the stops 48 will remain in operative position until near the end of the return motion of the key 42. However, after the main feed roller and the guide member 10 have been fully restored, the forward end of the slot 69 will engage with the screw 65 and then further movement of the link 67 will be transmitted to the crank arm 64, rocking the sleeve 54 and retracting the stops 48. The bill sheet is thus expeditiously adjusted and held in position for receiving the first line of writing thereon. If desired, the bail 71, 72 may be lifted or swung up and the upwardly extending portion of the bill sheet passed under the rod 72 so that the rollers 73 may press the bill sheet against the platen above the printing line.

It will be understood that a carbon sheet, which it has not been deemed necessary to show, is arranged between the bill sheet and the underlying record sheet so as to transfer the type impressions to the record sheet. In the case of a tax bill the bill is folded one or more times and carbon or transfer sheets are interleaved with the folds so that the items may be duplicated at a single writing. Ordinarily only a single line or at most a very few lines of writing or memoranda are written on each tax bill. It will be seen that by moving the deflector 10 away from the platen to provide a comparatively wide passage way which is unobstructed all the way from the front to the place where the end stops 48 project, a construction is provided which enables the bill, whether a single sheet, a folded sheet, or a plurality of separate sheets secured together, to be readily adjusted to the platen and thereafter held in position for receiving the writing, at what may be said to be a single operation and without the necessity of turning the platen for feeding the paper at all either forward 105 or backward.

It will be noted that while the curved lower portion of the deflector or guide 10 moves substantially radially of the platen the rear portion of the guide through which 110

the end stops project, is comparatively straight; and that this portion moves in an inclined downward direction lengthwise of itself while the movement of the paper stops 5 is in a direction transverse of this and nearly at right angles thereto. Said paper stops are arranged to move in vertical fore and aft planes, which planes pass between the terminal rolls and the main feed roller. Said terminal rolls are arranged outside of 10 or beyond the vertical planes passing fore and aft of the machine and containing the ends of the main feed roller.

What I claim as new and desire to secure 15 by Letters Patent, is:—

1. In a typewriting machine, the combination of a platen, a paper deflector, an end stop for the paper, means for affording movement of said deflector away from the 20 platen, and means for concurrently moving said stop toward the platen.

2. In a typewriting machine, the combination of a platen, a paper deflector curved to conform substantially thereto, a paper 25 stop, means for affording movement of said paper deflector away from the platen, and means for concurrently moving said paper stop substantially radially toward the platen and in a path transverse of the path of said deflector.

3. In a front-strike typewriting machine, the combination of a platen, a paper deflector normally engaged with the platen, said deflector curving around the under and 35 forward side thereof and terminating a short distance below the printing line, a paper stop independent of the deflector, a main feed roller arranged forward of said paper stop, and means for affording movement of said deflector away from the platen to provide an opening between the platen and the deflector through which the paper 40 may be introduced from the front side of the platen to coöperate with the paper stop.

4. In a front-strike typewriting machine, the combination of a platen, a paper deflector curving around the platen and terminating a short distance below the printing line, a paper stop at the rear of the platen 50 and normally in inoperative position, means for affording movement of the deflector away from the platen to provide an opening through which paper may be introduced from the front of the machine, and means 55 for concurrently moving said paper stop to operative position.

5. In a front-strike typewriting machine, the combination of a platen, a paper deflector curving around the platen and terminating a short distance below the printing line, a paper stop at the rear of the platen and normally in inoperative position, means for affording movement of the deflector away from the platen to provide an 60 opening through which paper may be intro-

duced from the front of the machine, and means for concurrently moving said paper stop to operative position, said paper stop moving toward the platen through an opening in said deflector but being separated 70 from the platen when in working position.

6. In a typewriting machine, the combination of a platen, a paper guiding member comprising a paper deflector coöoperative with the platen at its under side, a paper stop separate from and projecting through an opening in said member, means for movably supporting said member at two points one above the other, means for affording movement of said deflector in an inclined path downward and forward relatively to the platen, and devices for concurrently moving said paper stop into operative position in a path transverse of the path of the deflector.

7. In a typewriting machine, the combination of a platen, a paper deflector, a separate end stop for the paper, means for affording movement of said deflector away from the platen and for maintaining the 90 deflector in the released position, and devices for concurrently moving said stop toward the platen into operative position and for maintaining said stop in operative position.

8. In a typewriting machine, the combination of a platen, a paper deflector, a separate end stop for the paper, means for affording movement of said deflector away from the platen, and lost motion connections 100 between said means and said end stop.

9. In a typewriting machine, the combination of a platen, a paper deflector, a separate end stop for the paper, means for affording movement of said deflector away from the 105 platen, lost motion connections between said means and said end stop for concurrently moving said stop, and means for holding said stop in positions to which it may be moved.

10. In a typewriting machine, the combination of a platen, a paper deflector, an end stop for the paper, means for affording movement of said deflector away from the platen, lost motion connections between said 115 means and said end stop for concurrently moving said stop, and means comprising friction disks and an interposed washer for holding said stop in positions to which it may be moved.

11. In a typewriting machine, the combination of a platen, an end stop for the paper, a key, mechanical lost motion connections between said end stop and said key for affording movement of said end stop into and out of operative position, and friction means comprising coöperating friction disks for maintaining said end stop in positions to which it may be moved.

12. In a typewriting machine, the combi- 120

nation of a platen, an end stop for the paper, a single key actuated means for moving said end stop both into and also out of operative position, said means being normally passive and separate devices for maintaining said end stop in both operative and inoperative positions.

13. In a typewriting machine, the combination of a platen, a rotary device, a crank arm fixed thereto, an end stop on said crank arm, a second crank arm, a key, and mechanical and positive connections between said key and said second crank arm, said connections being operative to move said second crank arm in opposite directions.

14. In a typewriting machine, the combination of a platen, a rotary device, a crank arm fixed thereto, an end stop on said crank arm, a second crank arm, a key, lost motion mechanical and positive connections between said key and said second crank arm, said connections being operative to move said second crank arm in opposite directions, and devices coöperative with said rotary member to maintain it in set positions.

15. In a typewriting machine, the combination of a platen, a rotary sleeve, a crank arm fixed thereto, an end stop on said crank arm, a second crank arm, a key, a link connected to said key and having a pin and slot connection with said second crank arm, and frictional devices for maintaining said sleeve in set positions.

16. In a typewriting machine, the combination of a platen, a rotary sleeve, a crank arm fixed thereto, an end stop on said crank arm, a second crank arm, a key, a link connected to said key and having a pin and slot connection with said second crank arm, and frictional devices comprising relatively rotatable disks and an interposed washer for maintaining said sleeve in set positions.

17. In a typewriting machine, the combination of a platen, a combined paper table and deflector movably mounted, means for guiding said combined paper table and deflector comprising a rod; a sleeve rotatable on said rod; a paper stop supported on said sleeve and projective through an opening in said combined table and deflector; means for moving said deflector away from the platen, said moving means comprising a key; lost motion connections between said key and said sleeve; and friction holding devices for maintaining said sleeve and said paper stop in set positions.

18. In a typewriting machine, the combination of a platen; a combined paper table and deflector movably mounted; means for guiding said combined paper table and deflector comprising a rod; a sleeve rotatable on said rod; a paper stop supported on said sleeve and projective through an opening in said combined table and deflector; means for moving said deflector away from the

platen, said moving means comprising a key; lost motion connections between said key and said sleeve; and friction holding devices for maintaining said sleeve and said paper stop in set positions, said friction devices comprising a disk fixed on said rod, and a coöperating disk fixed on said sleeve.

19. In a typewriting machine, the combination of a platen, a paper deflector coöperative with said platen and affording a passage way for the paper leading from the front of the platen below the printing point around the under side of said platen, a paper stop, a main feed roller forward of the paper stop, and key controlled devices for moving said paper stop into and out of said passage way at will.

20. In a typewriting machine, the combination of a platen, a paper deflector coöperative with said platen and movable to afford a passage way for the paper leading from the front of the platen below the printing point around the under side of said platen, a paper stop; key controlled devices for moving said paper stop into and out of said passage way at will, means for maintaining the paper deflector set after it has been moved to position to provide the passage way aforesaid, and means for maintaining the paper stop in operative position projecting into said passage way.

21. In a typewriting machine, the combination of a platen, a paper deflector normally operatively engaged with the platen, a feed roller normally operatively engaged with the platen, a paper end stop normally inoperative, and means for concurrently moving said deflector out of contact with the platen, also for releasing said feed roller and also for moving said paper stop into operative position.

22. In a typewriting machine, the combination of a platen, a paper deflector, a main feed roller, terminal pressure rollers, a paper end stop, means for concurrently releasing said main feed roller and moving said deflector out of engagement with the platen and also for moving said end stop into operative position.

23. In a front-strike typewriting machine, the combination of a platen, a combined paper table and deflector extending around the platen from the front side thereof and upward at the rear side thereof, a main feed roller, terminal pressure rollers, a paper stop, a side guide for a record sheet when introduced at the rear of the machine, a side guide for a second sheet when introduced at the front of the machine, key controlled means for releasing the main feed roller and for throwing off the combined paper table and deflector to afford a passage from the front of the machine, and means operative by the same key for moving the paper stop into operative position.

24. In a typewriting machine, the combination of a platen, a releasable main feed roller, terminal pressure rolls, and key controlled paper stops movable in vertical fore 5 and aft planes, which planes pass between said terminal rolls and the outer ends of said main feed roller.
25. In a typewriting machine, the combination of a platen, a releasable main feed 10 roller, terminal pressure rolls arranged outside of the vertical fore and aft planes passing through the ends of the main feed roller, key controlled paper stops movable in vertical fore and aft planes, which planes pass 15 between said terminal rolls and the ends of said main feed roller, said stops being adapted to coöperate with the bottom edge of the work sheet introduced at the front of the machine, and a side guide at the front of the 20 machine for said work sheet.
26. In a typewriting machine, the combination of a platen, a paper deflector curving around the under and forward sides thereof and terminating below the printing line, 25 a feed roller, means for releasing the feed roller and concurrently moving the deflector to afford a passage for the introduction of the paper rearward from the front of the machine, a pressure bail coöoperative with 30 the platen above the printing line, and a side guide for the paper mounted on said pressure bail.
27. In a typewriting machine, the combination of a platen, a platen carriage, paper 35 guiding devices coöoperative with the platen below the printing line, a spring mounted pressure bail pivoted on said carriage and coöoperative with the platen above the printing line, and a side gage for the paper 40 mounted on said pressure bail.
28. In a front-strike typewriting machine, the combination of a platen; a paper deflector affording a passage around the platen from the front side thereof below the printing line, a pivotally mounted U-shaped pressure bail comprising a rod or bar extending 45 along the platen above the printing line, and a side gage adjustably mounted on said rod or bar and coöoperative with the side edge
- of the paper when introduced from the front 50 of the machine.
29. In a typewriting machine, the combination of a platen; paper feeding and guiding devices coöoperative therewith; a paper stop; means for releasing said devices comprising an eccentric strap connected to said devices, and a hand operated eccentric coöoperative with said strap; and connections 55 between said hand operated eccentric and said paper stop. 60
30. In a typewriting machine, the combination of a platen; paper feeding and guiding devices coöoperative therewith; a paper stop; means for releasing said devices comprising an eccentric strap connected to said 65 devices, and a hand operated eccentric coöoperative with said strap; and lost motion connections between said hand operated eccentric and said paper stop, said connections comprising a link having a pin and 70 slot connection with said paper stop.
31. In a typewriting machine, the combination of a platen carrier; a platen thereon; a rock shaft; a feed roller supported thereby; a paper guiding member; means on said 75 rock shaft for releasing said feed roller and said guiding member; a paper stop; hand operated devices for turning said rock shaft comprising a crank arm on said rock shaft, an eccentric strap pivotally connected to 80 said crank arm, and an eccentric member coöoperative with said strap and provided with a finger piece; and lost motion connections between said eccentric member and said paper stop, said lost motion connections 85 comprising a link connected to said eccentric member and having a pin and slot connection with a rotary sleeve on which said paper stop is supported.

Signed at the borough of Manhattan, city 90 of New York, in the county of New York and State of New York, this 29th day of Feb. A. D. 1912.

CLIO B. YAW.
